UNITED STATES PATENT OFFICE

2,567,618

FOUNTAIN PEN

Hadly W. Quaintance, Caldwell, Idaho

Application November 8, 1949, Serial No. 126,148

8 Claims. (Cl. 120—47)

1

This invention relates to a fountain pen and has for its primary object the provision of improved mechanism for filling the pen with ink. A further object is the provision of a pen characterized by its having substantially leak-proof qualities. Still another object resides in the provision of means precluding the ingress of lint and dust into the operating parts. Still other objects reside in the provision of a fountain pen which is sturdy and durable in construction, reliable and efficient in operation, relatively simple and inexpensive to manufacture and assemble, and highly ornamental and attractive in appearance. Other objects will in part be obvious and in part be pointed out as the description of the invention proceeds, and shown in the accompanying drawings, wherein is shown a preferred embodiment of the inventive concept.

In the drawings:

Figure 1 is a side sectional view of one form of fountain pen embodying the invention.

Fig. 2 is an enlarged fragmentary sectional view showing certain constructional details of Fig. 1.

Fig. 3 is a sectional view taken substantially along the line 3—3 of Fig. 2 as viewed in the direction indicated by the arrows.

Fig. 4 is an enlarged sectional view taken substantially along the line 4—4 of Fig. 2 as viewed in the direction of the arrows.

Fig. 5 is an inverted sectional view taken substantially along the line 5—5 of Fig. 4 as viewed in the direction of the arrows.

Fig. 6 is an enlarged sectional view taken substantially along the line 6—6 of Fig. 3 as viewed in the direction of the arrows.

Fig. 7 is an enlarged fragmentary sectional view showing certain additional details disclosed in Fig. 1.

Fig. 8 is a sectional view taken along the line 8—8 of Fig. 7 as viewed in the direction of the arrows.

Fig. 9 is a fragmentary view showing certain of the elements disclosed in Fig. 7, in a different position of adjustment.

Fig. 10 is a sectional view taken substantially along the line 10—10 of Fig. 9 as viewed in the direction indicated by the arrows, and

Fig. 11 is a perspective view of a further constructional detail.

Similar reference characters refer to similar parts throughout the several views of the drawings.

2

Having reference now to the drawings in detail, and more particularly to Fig. 1, there is generally indicated at 20 a pen barrel of any desired material such as transparent plastic, threaded as at 21 to receive a conventional cap (not shown) and provided with a conventional nub 22 and point 23, the latter being provided with the customary aperture in communication with an ink feeding and filling channel 24. Channel 24 opens into a recess 25 in which is seated a spring 26 which normally biases to open position a check valve 27 in a pressure chamber 28 in barrel 20 to permit normal free gravity feed of ink to point 23 from chamber 28. Chamber 28 is provided with an extending portion 29 of reduced diameter in which is positioned a piston 30 connected to a piston rod 31, the portion 29 terminating in an end wall 32 having a key hole slot 33 therein (see Fig. 10), into which rod 31 extends, the latter being provided with a depending longitudinally extending projection 34 filling the lower portion of slot 33, the purpose of which projection will be more fully pointed out hereinafter.

25 The major portion of barrel 20 is comprised of an ink reservoir 35 having an aperture 36 communicating with pressure chamber 28, a valve seat plate 37 being provided adjacent the aperture. Interiorly of reservoir 35 is a valve guide 38 comprised of a pair of extending members 39 having guide ridges 40 thereon (see Figs. 4 and 5), and terminating in a spring retaining flanged member 41 against which seats one end of a compression spring 42. The other end of spring 42 abuts a valve 43 normally biasing the valve towards aperture 36 to close the same except when held in open position in a manner to be later described. Valve 43 is provided with channels 44 engaged to guide ridges 40 to insure proper alignment. As best shown in Fig. 5, the inner ends 45 of members 39 may be bent and engaged in plate 37 to secure the parts in related assembly.

45 Means, as best shown in Figs. 2, 3 and 6, are provided for holding valve 43 in open position when piston 30 is in its innermost position and take the form of an arm 50 having one incurved end 51 adapted to be abutted by piston 30 and the other incurved end 52 adapted to abut valve 43. Arm 50 is formed integral with a sleeve 53 located intermediate its ends and adapted to receive a cross bolt 54 mounted in eyebolts 55 threaded at 56. Lever 50, as well as plate 37, is held in position by the eyebolts 55, engaged in internally threaded sleeves 57 passed through

suitable apertures in plate 37 and the end wall of ink reservoir 35. A screw 56' threaded into a sleeve 57' serves as additional securing means for the plate 37.

The end of reservoir 35 opposite valve 43 is provided with a normally closed pressure relief valve 60 adapted to seat in an aperture 61 in a threaded plug 62 positioned in a threaded aperture in an extending portion 63 of reservoir 35. Slots 64 are provided to permit the insertion of a suitable tool for removal or installation of plug 62. A spring 65 normally biases valve 60 towards closed position (see Figs. 7, 8 and 9).

Means are provided for opening spring valve 60 when plunger 31 is retracted and take the form of an apertured flanged bracket 66 (see Fig. 11), the flanges 67 of which are adapted to be inset in the end wall of the reservoir. The apertures are engaged by a pivot pin 68 extending from the fulcrum of a bell crank lever 69, one leg 70 of which is adapted to open valve 60 when the other leg 71 is abutted by projection 34 of piston rod 31. A channel 72 extending within portion 63 communicates with the hollow interior 73 of plug 62 to permit pressure relief from the reservoir.

The open end of slot 33 is protected as is the last described valve assembly against the ingress of dust or lint by means of an air pervious silk mat 75 apertured to permit extension of rod 31 the end of which is provided with a knob 76 to facilitate finger grasp.

Referring back to Fig. 1, it will be seen that barrel 20 is threaded as at 77 for engagement with corresponding threads of a protective cap 78 having a conventional pocket clip 79.

From the foregoing the operation of the device should now be readily understandable. In normal use of the pen, with the parts as shown in Fig. 1, the reservoir 35 being assumed to contain ink, valve 43 is open and valve 60 closed as above described, and spring 26 holding valve 27 open, ink will flow by gravity to point 23.

When it is desired however to refill reservoir 35, cap 78 is removed and piston 30 is retracted by means of rod 31. A pressure differential is thus created between pressure chamber 28 and atmospheric pressure which latter forces ink into chamber 28, valve 27 being open, simultaneous opening of valve 60 equalizing the pressure in the reservoir. Reverse movement of piston 30 during filling of the reservoir 35 serves to increase pressure in chamber 28 to a point sufficient to close valve 27 and open valve 43, thus forcing ink into reservoir 35. Obviously a few additional movements of piston 30 will serve to fill reservoir 35 to the desired degree.

It will now be seen that there is herein provided an improved fountain pen which accomplishes all the objects of the invention and others, including many advantages of great practical utility and commercial importance.

As many embodiments may be made of the inventive concept, and as many modifications may be made in the embodiment herein shown and described, it is to be understood that all matter herein is to be interpreted merely as illustration and not in a limiting sense.

Having thus described the invention, what is claimed is:

1. In a device of the character described, in combination a barrel, a nub having a passage therethrough, an apertured point communicating with said passage, means forming a pressure

chamber in said barrel normally in communication with said passage, a check valve mounted on the inner end of the nub operating between said chamber and said passage, means forming an extension to said chamber, a piston movable in said extension, a piston rod extending exteriorly of said barrel, an ink reservoir in said barrel, a connection between said chamber and said reservoir, a check valve spring biased towards closed

position in said last mentioned connection, and an operating lever operating the check valve, operable by said piston to open said check valve.

2. In a device of the character described, in combination a barrel, a nub having a passage therethrough, an apertured point communicating with said passage, means forming a pressure chamber in said barrel normally in communication with said passage, a check valve between said chamber and said passage, means forming an extension to said chamber, a piston movable in said extension, a piston rod extending exteriorly of said barrel, an ink reservoir in said barrel, a connection between said chamber and said reservoir, a check valve spring biased towards closed position in said last mentioned connection, and means independent of the piston, operable by said piston to open said last mentioned valve, said last mentioned means including a pivoted lever having inwardly curved ends upon abutment of one of which by said piston the other of which acts to open said last mentioned valve.

3. In a device of the character described, in combination a barrel, a nub having a passage therethrough, an apertured point communicating with said passage, means forming a pressure chamber in said barrel normally in communication with said passage, a check valve between said chamber and said passage normally spring biased to its open position releasing ink to the nub, means forming an extension to said chamber, a piston movable in said extension, a piston rod extending exteriorly of said barrel, an ink reservoir in said barrel and disposed laterally of the extension and piston, a connection between said chamber and said reservoir, a check valve spring biased towards closed position in said last mentioned connection, a lever engaging the latter check valve, engaged by the piston operating the latter check valve by contact with the piston, a pressure relief valve at the end of said reservoir opposite said last mentioned check valve, and a lever operated by said piston rod moving the pressure relief valve to an open position.

4. In a device of the character described, in combination a barrel, a nub having a passage therethrough, an apertured point communicating with said passage, means forming a pressure chamber in said barrel normally in communication with said passage, a check valve between said chamber and said passage normally spring biased to its open position releasing ink to the nub, means forming an extension to said chamber, a piston movable in said extension, a piston rod extending exteriorly of said barrel, an ink reservoir in said barrel and disposed laterally of said extension to said chamber, a connection between said chamber and said reservoir, a check valve spring biased towards closed position in said last mentioned connection, means operated by the movement of the piston, adapted to open the second mentioned check valve, a pressure relief valve at the end of said reservoir opposite said last mentioned check valve, means operated by the outward movement of the piston rod for opening

said relief valve, and spring means biasing said pressure relief valve towards closed position.

5. In a device of the character described, in combination a barrel, a nub having a passage therethrough, an apertured point communicating with said passage, means forming a pressure chamber in said barrel normally in communication with said passage, a check valve between said chamber and said passage normally spring baised to its open position releasing ink to the nub, means forming an extension to said chamber, a piston movable in said extension, a piston rod extending exteriorly of said barrel, an ink reservoir in said barrel, a connection between said chamber and said reservoir, a check valve spring biased towards closed position in said last mentioned connection, a lever engaging the second mentioned check valve, operated by said piston opening the last mentioned check valve, a pressure relief valve at the end of said reservoir opposite said last mentioned check valve, spring means biasing said pressure relief valve towards closed position, and means operable by said piston rod for opening said pressure relief valve.

6. In a device of the character described, in combination a barrel, a nub having a passage therethrough, an apertured point communicating with said passage, means forming a pressure chamber in said barrel normally in communication with said passage, a check valve between said chamber and said passage normally spring baised to its open position releasing ink to the nub, means forming an extension to said chamber, a piston movable in said extension, a piston rod extending exteriorly of said barrel, an ink reservoir in said barrel, a connection between said chamber and said reservoir, a check valve spring biased towards closed position in said last mentioned connection, means operated by said piston for opening the second mentioned check valve, releasing ink to the pressure chamber, a pressure relief valve at the end of said reservoir opposite said last mentioned check valve, spring means biasing said pressure relief valve towards closed position, means operable by said piston rod for opening said pressure relief valve, said last mentioned means including a bell crank lever adjacent said last mentioned valve and a projection carried by said piston engageable with one arm of said bell crank lever to cause the other arm thereof to open said pressure relief valve.

7. In a device of the character described, in combination a barrel, a nub having a passage therethrough, an apertured point communicating with said passage, means forming a pressure chamber in said barrel normally in communication with said passage, a check valve between said chamber and said passage normally spring baised to its open position releasing ink to the nub, means forming an extension to said chamber, a piston movable in said extension, a piston

rod extending exteriorly of said barrel, an ink reservoir in said barrel, a connection between said chamber and said reservoir, a check valve spring biased towards closed position in said last mentioned connection, a lever mounted in the pressure chamber engaging the last mentioned check valve, operated by said piston opening the last mentioned check valve releasing ink to the pressure chamber, a pressure relief valve at the end of said reservoir opposite said last mentioned check valve, spring means biasing said pressure relief valve towards closed position, means operable by said piston rod for opening said pressure relief valve, said last mentioned means including a bell crank lever adjacent said last mentioned valve, a projection carried by said piston engageable with one arm of said bell crank lever to cause the other arm thereof to open said pressure relief valve, and means protecting the last mentioned valve assembly from dust.

8. In a device of the character described, in combination a barrel, a nub having a passage therethrough, an apertured point communicating with said passage, means forming a pressure chamber in said barrel normally in communication with said passage, a check valve between said chamber and said passage normally spring baised to its open position releasing ink to the nub, means forming an extension to said chamber, a piston movable in said extension, a piston rod extending exteriorly of said barrel, an ink reservoir in said barrel, a connection between said chamber and said reservoir, a check valve spring biased towards closed position in said last mentioned connection, piston operated means in the pressure chamber adapted to move the last mentioned check valve to open position, a pressure relief valve at the end of said reservoir opposite said last mentioned check valve, spring means biasing said pressure relief valve towards closed position, means operable by said piston rod for opening said pressure relief valve, said last mentioned means including a bell crank lever adjacent said last mentioned valve, a projection carried by said piston engageable with one arm of said bell crank lever to cause the other arm thereof to open said pressure relief valve, and means protecting the last mentioned valve assembly from dust, said last mentioned means including a silk mat apertured to permit passage of said piston rod.
